UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed August 16, 1923, Serial No. 657,670. Renewed October 6, 1924.

This invention relates to typewriting machines of the fan-fold class, such, for example as that disclosed in the patent to Wernery and Smith, No. 1,132,055, dated 5 March 16, 1915. In machines of this class a multiple-ply work-web having a succession of printed sets of forms thereon is led into the machine and fed around the platen line by line. Carbon-carrying blades extend between the plies of web, these being mounted upon a carrier or holder which is shifted longitudinally of the web from time to time as the typing of each set of forms on the web is completed, to strip the carbons from 10 the completed set of forms and interleave them with the next set.

At the line-spacing operation, the platen revolves, and by means of the usual feed-rolls advances the web, together with the carbons, and the carbon-holder or carrier, which is mounted to slide towards and away from the platen, as required, is drawn forward by the web and carbons. Owing to the weight of the web and to the weight of 15 the carbon-carrier the web is apt to slip with reference to the platen, causing the line feeding to be faulty, especially when the platen is jerked around, as it often is, by reason of too speedy manipulation of the 20 line-space lever, or by reason of the use of an electric motor to return the carriage and operate the line-feeding mechanism.

It has been proposed to prevent this faulty line feeding of the web, due to the inertia 25 of the plies of the web and of the carbon-carrier, by causing the carbon-carrier to occupy a normal position close to the platen, and the plies of web and carbon to form an upstanding loop between the carbon-carrier 30 and the platen. The carbon-carrier, as a result of this arrangement, does not have to move at the line-spacing operations; and only a short reach of web, which is between the carbon-carrier and the platen, is pulled 35 upon, and hence the inertia is insignificant and does not tend to make the line-spacing uneven. This loop of web is gradually taken up as the line-spacing proceeds, until by the time the typing of a set of forms is completed the loop is substantially all taken up.

For the purpose indicated above, provision is made in the machine of the present invention of means, preferably including a spring, for automatically returning the car-

bon-carrier to the forward limit of its movement as soon as it is released by the operative after having been thrust to the rear to interleave the carbons with a fresh set of forms.

In order to secure the desired co-operation of the web with the carbon-carrier, there is provided a clamp for clipping the web to the carbon-carrier. In accordance with an important feature of the present invention, this clamp is automatically controlled by the carbon-carrier operating means, being released by the actuation of the operating means to move the carbon-carrier to the rear, before any rearward movement of the carbon-carrier has taken place, and being clamped by the initial movement of the operating means to restore the carbon-carrier to its normal forward position, before any forward movement of the carbon-carrier has taken place. By this provision, it is assured that the carbon-carrier will be able to move freely to the rear with relation to the work-web in the usual manner for shifting the carbons to a fresh set of forms, but that movement of the carbon-carrier and the work-web in the forward movement of the carbon-carrier, which would tend to rumple the carbon-sheets and otherwise interfere with the desired operation, will be prevented.

The carbon-carrier is usually provided with a handle directly attached to it, which extends forwardly over the typewriter carriage to be reached by the operative. This handle is usually of great length, and when in its forward position extends over the keyboard, and therefore the objection arises that this handle would be in the way if the carbon-carrier were in its forward position practically all the time, which is the case in carrying out the present invention.

To overcome this objection, there is provided an operator for said carbon-carrier, in place of the usual handle, which comprises lazy-tongs or levers, or some other movable multiplying and transposing device, connected to the typewriter carriage and to the carbon-carrier thereon. This operator includes a handle which stands upright to the rear of the carriage when the carbon-carrier is in its normal position near the platen, so that it is not in the way, and which is swung forward by the operator to move the carbon-carrier to the rear.

The movement of the handle may be very much less than that of the carbon-carrier due to the multiplying connections, so that it will be unnecessary for the hand of the operative to be moved an excessive distance in effecting the shifting of the carbons.

It is also a feature of this invention that the spring for returning the carbon-carrier to its normal forward position is connected to act upon the carbon-carrier through the multiplying connections of the operator. This makes it possible to use a small strong spring for the purpose, which moves the carbon-carrier the full distance of its travel by a relatively slight contracting movement, and yet with substantially constant force.

Other features and advantages will hereinafter appear.

In the accompanying drawings,

Figure 1 is a sectional side elevation of a portion of the machine, showing the carbon-carrier in its normal advance position preparatory to beginning the typing of a set of forms.

Figure 2 is a view similar to Figure 1, showing the parts in the positions occupied at the completion of the typing of a set of forms.

Figure 3 is a plan view of the carriage and carriage extension, showing the carbon-carrier at its rear limit of movement.

Figure 4 is a view similar to Figure 1, showing the platen displaced and the carbon-carrier retracted.

Figure 5 is a view similar to Figure 1, showing the parts in the positions occupied preparatory to tearing off the completed set of forms.

The invention is shown as applied to an Underwood continuous billing machine of the kind disclosed in the abovementioned patent to Wernery and Smith, in which type-bars 10 are operated by keys (not shown) to swing upwardly and rearwardly to print against the front of a cylindrical platen 11. The platen 11 is mounted in a swing-frame 12 supported on a carriage 13, which comprises end bars 14 connected to each other by a rear bar 15 and a front bar, not shown. The carriage is mounted for letter feed and return movements upon rails (not shown), said rails being supported on the main frame of the machine. The platen is secured upon an axle 16 journaled in end plates 17 of the swing-frame and may be line-fed by a line-space lever (not shown) through connections including gears 18 and 19 and a pinion 20, as is usual in machines of this kind. The machine also includes a horizontal frame 21 which forms a rear extension of the carriage 13 and is connected to travel with the carriage. This frame comprises rails 22 on which a carbon-carrier 23 is mounted to travel toward and from the platen 11. A work-web 24 is led

over the carriage extension 21 from the rear and across the carbon-carrier 23 where the plies of the web become interleaved with carbons 25 carried by blades 26 on the carbon-carrier, and thence is led forward to 70 and around the platen 11.

The carbon-carrier 23 is retracted by an operator comprising a handle 27 pivoted at 28 upon the carriage extension 21 and a lazy-tongs 29, the operator handle 27 being 75 an upward extension of a link 30 at the forward end of the lazy-tongs. The lazy-tongs 29 is connected at its rear end to the carbon-carrier 23 through a pin 31 of the lazy-tongs and an arcuate slot 32 formed in 80 a bracket 33 on the carbon-carrier 23, the slot permitting limited lost motion between the lazy-tongs and the carbon-carrier for a purpose which will be pointed out herein-after. The lazy-tongs 29 is extended to the 85 rear to retract the carbon-carrier 23 by swinging the handle 27 forward, and is collapsed to draw the carbon-carrier forward by a tension spring 34 connected at its rear end to a pin 35 on the carriage extension 90 21 and at its front end to the handle 27 to draw the handle to the rear.

By the disclosed arrangement the carbon-carrier 23 is caused normally to occupy a position near the platen 11, and yet the 95 operator handle 27 is caused normally to occupy an upright position at the rear of the carriage 13 where it is out of the way. The movement of the operator handle 27 is short as compared with the travel of the 100 carbon-carrier 23 due to the multiplication effected by the lazy-tongs 29.

It is important to prevent shifting of the work-web 24 to the rear relatively to the carbons 25 as the carbon-carrier 23 is drawn forward, since this would rumple the carbons and otherwise interfere with the desired operation, but it is necessary too that the work-web and carbons be free to move relatively during the rearward movement 110 of the carbon-carrier. A clamp 36 is pivoted at 37 upon a bracket 38 on the carbon-carrier 23 for clamping the work-web 24 and carbons 25 against relative movement. This clamp 36 has a downwardly-extending 115 controlling arm 39 which is pivotally connected at its lower end to the pin 31 that connects the lazy-tongs 29 to the carbon-carrier 23. The slot 32 is curved about the pivot 37 of the clamp 36, so that the pin 31, 120 which is constrained to move in an arc having said pivot 37 for its center, may travel along the slot 32 to open and close the clamp.

At the beginning of typing a set of forms, 125 the parts are in the positions indicated in Figure 1, the carbon-carrier 23 being held at the forward limit of its movement against a fixed stop 40 on the carriage extension 21, by the spring 34. The clamp 130

36 is in effective position due to the fact that the pin 31 is drawn to the forward end of the slot 32 by the lazy-tongs 29. The typing then proceeds until the first set of 5 forms has been completely typed. If the typing runs to the bottom of the forms all of the slack will be taken out of the web by the successive line-spacing operations, as seen in Figure 2. The platen 11 is then dis- 10 placed, the work-web 24 is drawn forward to a gage 41, and the carbon-carrier 23 is retracted by operation of the handle 27, as seen in Figure 4, to shift the carbons 25 into co-operative relation with the next set of 15 forms on the web. The first result of the actuation of the handle 27 is to move the pin 31 to the rear end of the slot 32 which swings the arm 39 to release the work-web 24 and carbons 25 from the clamp 36. 20 After this the continued movement of the handle 27 retracts the carbon-carrier 23. The platen 11 is then lowered to its normal position and the handle 27 is released by the operator. The spring 34 at once draws 25 the handle 27 back to its normal upright position and this collapses the lazy-tongs 29. The collapsing of the lazy-tongs 29 first moves the pin 31 to the forward end of the slot 32, closing the clamp 36 upon the 30 work-web and carbons, and then moves the carbon-carrier 23 forward to its normal position, as seen in Figure 5, thereby creating slack in the web 24 to be drawn upon in typing the succeeding set of forms. The 35 completed set of forms is then torn from the web by means of a tearing-off knife 42 and the typing of the next set of forms is begun.

Variations may be resorted to within the 40 scope of the invention, and portions of the improvements may be used without others.

Having thus described my invention, I claim:

1. In a continuous billing typewriting machine for typing upon a continuous work-web, a carriage, a cylindrical platen journaled therein, a rear carriage extension, a carbon-carrier movable upon the carriage extension toward and from the platen, 45 means for keeping the carbon-carrier normally in a forward position near the platen to maintain slack in the work-web, a handle on the carriage for moving the carbon-carrier, and connections between the handle and carbon-carrier to cause movement of the handle to the front to move the carbon-carrier to the rear and vice versa, so that the handle will be caused to occupy a rearward position where it will be out of the 50 way when the carbon-carrier is in its normal forward position.

2. In a continuous billing typewriting machine for typing upon a continuous work-web, a carriage, a cylindrical platen journaled therein, a rear carriage extension, a 55

carbon-carrier on the rear carriage extension, means for moving the carbon-carrier toward and from the platen, comprising a handle on the carriage, connections between the handle and the carbon-carrier for causing the carbon-carrier to be moved to the rear by a forward movement of the handle, and a spring for swinging the handle to the rear to draw the carbon-carrier forward, 60 said spring being effective to cause the carbon-carrier to occupy a normal forward position near the platen, and the handle to occupy a normal rearward position out of the way of the operator. 70

3. In a continuous billing typewriting machine for typing upon a continuous work-web, a carriage, a cylindrical platen thereon, a clamp for clamping the work-web, a handle on said carriage, and means for moving the clamp forward toward the platen to 75 create slack in the work-web as the handle is moved to the rear.

4. In a continuous billing typewriting machine for typing upon a continuous work-web, a carriage, a cylindrical platen journaled therein, a rear carriage extension, a carbon-carrier movable toward and from the platen on the carriage extension, a handle on said carriage and movable toward the rear to move the carbon-carrier forward, 80 and means for retaining the handle at the rear limit of its movement whereby the carbon-carrier will be held at the forward limit of its movement to maintain slack in the work-web and thus prevent tension on the 85 work-web at the line-spacing operation. 90

5. In a continuous billing typewriting machine for typing upon a continuous work-web, a carriage, a cylindrical platen journaled therein, a rear carriage extension, a carbon-carrier movable toward and from the platen upon the rear carriage extension, a handle pivoted on the carriage extension and swingable forward to move the carbon-carrier to the rear away from the platen to 95 interleave the carbons with a fresh stretch of web, and means automatically to swing the handle to the rear as soon as it is released by the operator. 100

6. In a continuous billing typewriting machine for typing upon a multiple-ply continuous work-web, a cylindrical platen, a carbon-carrier movable toward and from the platen for holding carbons interleaved with the plies of the work-web, a normally effective clamp for clamping the work-web and carbons against relative movement, and means for moving the carbon-carrier to the rear to shift the carbons relatively to the work-web, said means being constructed automatically to unlock the clamp. 115

7. In a continuous billing typewriting machine for typing upon a multiple-ply continuous work-web, a cylindrical platen, a carbon-carrier movable toward and from the 120

- platen for holding carbons interleaved with the plies of the work-web, a handle for moving the carbon-carrier to the rear to interleave the carbons with a fresh stretch of the web and for moving the carbon-carrier forward to create slack in the web and carbons, lost-motion connections between the handle and the carbon-carrier, a clamp for clamping the work-web and carbons against relative movement, and means actuated by the handle for making the clamp effective as an incident of the operation of the handle for moving the carbon-carrier forward but prior to such movement of the carbon-carrier and for making the clamp ineffective as an incident of the operation of the handle for moving the carbon-carrier rearward but prior to such movement of the carbon-carrier.
20. 8. In a continuous billing typewriting machine for typing upon a multiple-ply continuous work-web, a cylindrical platen, a carbon-carrier movable toward and from the platen for holding carbons interleaved with the plies of the work-web, a handle for moving the carbon-carrier to the rear to interleave the carbons with a fresh stretch of the work-web and for moving the carbon-carrier forward to create slack in the web and carbons, a clamp for clamping the work-web and the carbons against relative movement, and means automatically controlled by the handle for causing the clamp to be ineffective during rearward movement of the carbon-carrier and to be effective at all other times.
9. In a typewriting machine, a cylindrical platen, a clamp, and means for moving the clamp toward and from the platen, said means being constructed and arranged automatically to open the clamp just prior to its movement away from the platen and to maintain it open throughout said movement and automatically to close the clamp just prior to its movement toward the platen and to maintain it closed throughout said movement to create slack in the work-web.
10. In a continuous billing typewriting machine for typing upon a multiple-ply continuous work-web, a cylindrical platen, a carbon-carrier movable toward and from the platen, a clamp pivoted on the carbon-carrier to clamp the work-web and carbons against relative movement, an operator for said carbon-carrier comprising a pin received in a slot of the carrier, said pin being also connected to the clamp and being so arranged that when moved to the rear it will first swing the clamp to open position and then move the carbon-carrier to the rear away from the platen to shift the work-web relatively to the carbons and when moved to the front it will first swing the clamp to closed position and then move the carbon-carrier to the front toward the platen

to create slack in the work-web and carbons.

11. In a continuous billing typewriting machine, a cylindrical platen, a carbon-carrier movable toward and from the platen, an operator for the carbon-carrier, lost-motion connections between the operator and the carbon-carrier, and a clamp actuated by relative movement of the operator and carbon-carrier to move to an open position in the initial movement of the operator to move the carbon-carrier away from the platen and to move to closed position in the initial movement of the operator to move the carbon-carrier toward the platen. 70

12. In a continuous billing typewriting machine, a cylindrical platen, a carbon-carrier movable toward and from the platen, a clamp pivoted on the carbon-carrier for holding the work-web and carbons against relative movement, a pin on the clamp, the carbon-carrier having an arcuate slot curved about the pivot of the clamp as a center in which the pin travels, and an operator for the carbon-carrier connected to said pin, the arrangement being such that upon actuation 85 of the operator to move the carbon-carrier away from the platen the pin first moves to the rear end of the arcuate slot opening the clamp and then thrusts the carbon-carrier to the rear, and upon actuation of the operator to move the carbon-carrier toward the platen the pin first moves to the forward end of the slot closing the clamp and then thrusts the carbon-carrier forward. 90

13. In a continuous billing typewriting machine for typing upon a multiple-ply continuous work-web, a cylindrical platen, a carbon-carrier, an operator for moving the carbon-carrier toward and from the platen, a spring acting on the operator to draw the carbon-carrier forward toward the platen, a clamp arranged to be automatically swung to effective position by said spring, and a stop to arrest the forward movement of the carbon-carrier with the spring under tension so that the effective condition of the clamp will be maintained in the forward position of the carbon-carrier. 100

14. In a continuous billing typewriting machine, a carriage, a cylindrical platen journaled therein, a rear carriage extension, a carbon-carrier mounted for movement on the carriage extension toward and from the platen, and an operator for the carbon-carrier comprising a handle on said carriage and multiplying connections between the handle and the carbon-carrier whereby the carbon-carrier may be retracted by a relatively short stroke of the handle. 115

15. In a continuous billing typewriting machine, a carriage, a cylindrical platen journaled therein, a rear carriage extension, a carbon-carrier mounted for movement on the carriage extension toward and from the platen, a handle on said carriage for mov- 120 125 130

ing the carbon-carrier, and connections between the handle and the carbon-carrier constructed and arranged to cause a movement of the handle in one direction to effect a greater movement of the carbon-carrier in the opposite direction.

16. In a continuous billing typewriting machine, a carriage, a cylindrical platen journaled therein, a rear carriage extension, a carbon-carrier mounted for right-line movement on the carriage extension toward and from the platen, and an operator for the carbon-carrier comprising a pivoted handle and a lazy-tongs connection between the handle and the carbon-carrier to retract the carbon-carrier a greater distance than the handle is moved.

17. In a continuous billing typewriting machine, a carriage, a cylindrical platen journaled therein, a carbon-carrier mounted for movement toward and from the platen, and a carbon-carrier operating means comprising a lazytongs, a handle for expanding the lazy-tongs to move the carbon-carrier away from the platen and a spring for collapsing the lazy-tongs to move the carbon-carrier toward the platen.

18. In a continuous billing typewriting machine, a cylindrical platen, a rear carriage extension, a carbon-carrier mounted for movement on the carriage extension toward and from the platen, a handle on said carriage for moving the carbon-carrier away from the platen, multiplying connections between the handle and the carbon-carrier for causing a long movement of the carbon-carrier to be effected by a relatively short movement of the handle, and a spring for moving the carbon-carrier toward the platen, the said spring being connected to the handle to act on the carbon-carrier through the multiplying connections so that the desired movement of the carbon-carrier may

be effected by a very short movement of the spring.

19. In a continuous billing typewriting machine, a carriage, a cylindrical platen journaled therein, a carbon-carrier mounted for movement toward and from the platen, and carbon-carrier operating means comprising a lazy-tongs, a handle swingable in one direction to expand the lazy-tongs to move the carbon-carrier away from the platen, and a spring for collapsing the lazy-tongs to move the carbon-carrier toward the platen, the said spring being connected to act upon the handle near its pivot so that a small spring may be used to move the carbon-carrier the desired distance.

20. In a typewriting machine, the combination with a carriage, a revolute platen and a carbon-carrier mounted at the rear thereof for movement bodily towards and from the platen, of a handle at the front of the carriage, a support on said carriage on which said handle is mounted, and a movement-multiplying device between said handle and said carbon-carrier.

21. In a continuous billing typewriting machine for typing upon a continuous work-web, a carriage, a cylindrical platen journaled therein, a rear carriage extension, a carbon-carrier on the rear carriage extension, means for moving the carbon-carrier toward and from the platen, comprising a handle, connections between the handle and the carbon-carrier, and a spring for swinging the handle to the rear to draw the carbon-carrier forward, said spring being effective to cause the carbon-carrier to occupy a normal forward position near the platen, and the handle to occupy a normal rearward position out of the way of the operator.

JESSE A. B. SMITH.
